ENDLESS OFFSET SHEET

Application filed July 11, 1928. Serial No. 291,939.

This invention relates to improvements in printing presses and has especial reference to rotary presses, an object being to provide an endless offset sheet for the second impression roller which may be repeatedly used, means being provided for guiding a continuous sheet around said roller and for cleaning and drying the sheet after it leaves the roller, so that a dry clean surface will be continuously presented at the second impression roller of the press.

Another object of the invention is the provision of an offset sheet which will be cleaned and fed to the second impression roller without rewinding or removing the sheet from the press, the character of the sheet, together with the manner of mounting and operation, adding materially to the life of the sheet, so that the cost of handling and materials will be greatly reduced.

Another object of the invention is the provision of means for mounting and attaching the sheet and its operating and cleaning mechanism to a press, so that the invention may be supplied as a press accessory, or may be installed at the time of manufacture of the press.

With the above and other objects in view, the invention further includes the following novel features and details of construction, to be hereinafter more fully described, illustrated in the accompanying drawings and pointed out in the appended claims.

In the drawings:-

Figure 1 is a fragmentary elevation showing a portion of a rotary printing press with the invention applied.

Figure 2 is a section on the line 2-2 of Figure 1.

Referring to the drawings in detail wherein like characters of reference denote corresponding parts, the reference character 10 indicates a portion of the frame of the press while 11 indicates a portion of the second impression cylinder. By this is meant the cylinder around which the web 12 passes after the first side of the web or paper has been printed.

As is well known, a sheet (called the offset sheet) is passed between the second impres-

sion cylinder and the printed side of the web so that this cylinder will be kept free of ink to prevent the printed side of the web from becoming blurred. Ordinarily, this is a special paper run from a large roll and after being run, must be rewound. The paper is costly and deteriorates rapidly and this added to the time and labor required to rewind the offset sheet renders it very expensive.

These and other disadvantages are overcome in the present invention by providing a continuous offset sheet of relatively long life which need not be rewound or otherwise independently handled, and one which may be cleaned after it leaves the second impression cylinder, so that a continuous clean surface is provided for contact with the web at this point.

In the present instance the invention is shown as attached to a rotary press and for this purpose there is provided a frame 13 which is secured to the frame of the press. This frame 13 carries the rollers which drive and guide an endless offset sheet 14 which passes around the impression cylinder 11. The sheet 14 passes between traction rollers 15 and 16, the latter being adjustable with respect to the former by means of an adjusting screw 17, and suitable spring means may be provided to keep the roller 15 in proper frictional contact with the sheet 14. The sheet 14 also passes around a roller 18 which is adjustable to regulate the tension of the sheet, and for this purpose is mounted in adjustable bearings 19.

The sheet also passes around rollers 20, 21, 22 and 23 which are positively driven by suitable means from the press, the driving means being such that the peripheral speeds of the rollers are at all times in synchronism. This insures that friction of the offset sheet around the rollers will be reduced to a minimum and that the pull upon the splice of the sheet at its connected ends will be reduced, so that the life of the sheet will be materially increased. The spring adjustment of the roller 16 insures a constant pressure on the sheet irrespective of the thickness of the latter.

The sheet 14 further passes around a guide

100

roller 24 and a tension roller 25. This last mentioned roller is mounted at the outer ends of pivoted arms 26 whose movement in one direction is yieldingly resisted by a spring 5 27.

10 The sheet 14 passes between the roller 21 and a roller 28. This last mentioned roller operates within a reservoir 29 which preferably contains oil or other ink solvent. The cylinder 28 is adjustable with respect to the cylinder 21 through the medium of an adjusting screw 29 which regulates the position of adjustable bearings 30 for the cylinder 28. The amount of oil or other solvent applied to the sheet 14 may thus be regulated.

15 Bearing against the sheet 14 are cleaning and drying elements 31 and 32 respectively. These elements each include frames 33 which are movable upon rods 34. The frames 33 20 carry flexible wiping elements 35 which bear upon the sheet and which are yieldingly forced into engagement by means of springs 36. These springs may be tensioned by means of adjusting nuts 37. Located below the sheet and carried by the frame 13 is a drain pan 38.

25 The sheet 14 is treated with a special coating consisting of a mixture of celluloid and acetone, which renders the treated surface 30 impervious to oil, ink and other moisture. However, the sheet possesses such resilience and flexibility that the prepared surface will not crack or break down under the pounding of the type.

35 When the ink from the first impression upon the web 12 is transferred to the offset sheet 14 at the second impression cylinder 11, the sheet carries this ink to the rollers 21 and 28. At this point the ink is covered with 40 oil or other solvent by contact with the cylinder 28 and when the treated portion of the sheet reaches the cleaning element 31, the ink and oil is removed from the sheet. When the sheet reaches the drying element 32, any 45 oil or other moisture remaining upon the sheet is effectually removed, while the drain pan 38 directs this oil back into the reservoir 29. As the sheet travels in the direction indicated by the arrow in Figure 2, a 50 clean dry surface will be presented to the second impression cylinder.

55 The invention is susceptible of various changes in its form, proportions and minor details of construction and the right is here- 55 in reserved to make such changes as properly fall within the scope of the appended claims.

Having described the invention what is claimed is:

60 1. In combination with a rotary printing press, an offset sheet having a ductile resili- 60 ent coating impervious to moisture, means to direct the offset sheet around the impres- 65 sion cylinder of the press between said cylinder and the web, and means to clean the offset

sheet after the latter leaves the impression cylinder.

2. In combination with a rotary printing press, an offset sheet impervious to moisture, means to direct the sheet around the impres- 70 sion cylinder of the press between the cylinder and web, means to distribute an ink solvent over the sheet after the latter leaves said cylinder, means to remove the ink solvent from the sheet and an inclined drain pan carried by the press beneath the ink solvent removing means to direct the removed solvent to the solvent distributing means.

75 In testimony whereof we affix our signatures.

80 JAMES ELMORE GUERRY.
FREDERICK WILLIAM WORRALL.
